(57) **CLAIM**

I claim the ornamental design for a paint bucket liner, as shown and described.

DESCRIPTION

FIG. 1 is a perspective view showing principally lower portions of a first form of my new design;

FIG. 2 is a perspective view showing principally upper portions thereof;

FIG. 3 is front side elevational view thereof;

FIG. 4 is a rear elevation view thereof;

FIG. 5 is a left side elevation view thereof, the right side elevation view being a mirror image;

FIG. 6 is a top plan view thereof;

FIG. 7 is a bottom plan view thereof;

FIG. 8 is a bottom perspective view of a paint bucket liner showing a second embodiment of the present invention;

FIG. 9 is a top perspective view thereof;

FIG. 10 is front elevation view thereof;

FIG. 11 is a rear elevation view thereof;

FIG. 12 is a left side elevation view thereof, the right side elevation view being a mirror image;

FIG. 13 is a top plan view thereof; and,

FIG. 14 is a bottom plan view thereof.

The broken lines in FIGS. 8, 9, 10, 11, 12 and 14 are used to show the paint bucket liner having no particular length and forms no part of the claimed design.

The innermost broken line in original FIGS. 2, 6 and 9, and in original FIGS. 14 and 18 (renumbered herein as FIGS. 9 and 13) is a boundary line, which forms no part of the claimed design.
